DRILLING MUD BY-PASS FOR ROTARY DRILL BITS

William D. Myers, Norwalk, Calif., assignor, by mesne assignments, to Houston Oil Field Material Company, Inc., Houston, Tex., a corporation of Delaware

Filed Sept. 30, 1957, Ser. No. 687,216

5 Claims. (Cl. 255—24)

The present invention relates to the drilling of well bores by the rotary method, in which drilling mud is circulated through the drilling string and drill bit for the primary purpose of removing the cuttings produced by the drill bit and flushing them to the top of the well bore.

Rotary drill bits employed in the drilling of well bores may contain nozzles or outlet openings of relatively small area for the purpose of discharging drilling fluid at a high velocity directly toward the bottom of the hole, the drill bit cutters, or both. The small area of the openings in the drill bit nozzles restricts the flow of the drilling mud in the well bore into the tubular drilling string while it is being lowered within the well bore. The restricted openings through which the drilling mud must pass may result in damage to the formation caused by the drilling string and bit functioning as a giant piston as they are lowered in the well bore, which builds up a comparatively high pressure in the drilling mud and forces it into the formation.

The restricted fluid circulation area through the drill bit also decreases the ease with which the drilling mud can drain from the drill pipe or other tubular drilling string when it is being removed from the well bore. The result is often the spilling of the drilling mud on the derrick floor when each stand of drill pipe is disconnected. In some instances, it results in the drill pipe performing a swabbing action in the well bore while being elevated therein, with the hazard of producing a blow-out.

An object of the invention is to provide an improved apparatus which enables the fluid in the well bore to bypass around the drill bit into the drilling string as the latter is being lowered in the well bore and also while the drilling string is being elevated therewithin, such bypassing being prevented during the time drilling fluid is being pumped downwardly through the drill string. By employing such an apparatus, high pressure in the well bores cannot be developed as a result of lowering the drill string therewithin, nor will the drilling string swab the well bore or tend to retain the drilling fluid during its elevation in the well bore.

Another object of the invention is to provide an apparatus of the character indicated which has a substantially unobstructed passage therethrough so as to avoid impedance to the flow of drilling fluid down through the drilling string during the drilling operation.

A further object of the invention is to provide a fluid by-pass apparatus in a drilling string which is of simple construction, economical to manufacture, and easy to maintain in proper operating condition.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but

it is to be understood that such detailed description is not to be taken in a limiting sense, since the scope of the invention is best defined by the appended claims.

Referring to the drawings:

- 5 Figure 1 is a combined longitudinal section and side elevation of an apparatus being moved in a well bore; Fig. 2 is an enlarged fragmentary section of part of the apparatus shown in Fig. 1; Fig. 3 is a side elevation, as seen from the right of Fig. 2.
- 10 The apparatus illustrated in the drawings includes a rotary drill bit A of any suitable type connected to the lower end of a string of drill pipe B, or corresponding tubular drilling string, extending to the top of the well bore C. As is well known, the string of drill pipe is rotated to rotate the drill bit in accomplishing the drilling operation, the drill bit cutters 10 operating upon the bottom of the well bore while drilling mud is being pumped down through the drilling string and through
- 15 the nozzle or nozzles 11 in the drill bit for the purpose of removing the cuttings and flushing them around the exterior of the drilling string to the top of the hole.
- 20

An apparatus C forming part of the drilling string is designed to allow fluid to by-pass around the drill bit nozzles 11 during lowering of the drill string and bit in the well bore, as well as during its elevation therewithin. However, during the actual drilling operation the fluid being pumped down through the drill string closes the by-pass device C to cause all of the drilling fluid to

25 pass through the drill bit nozzles 11 for the purpose of maintaining the bottom of the hole and the drill bit cutters 10 free and clean of cuttings.

As disclosed, the by-pass apparatus C includes a tubular body 15 which may have a lower threaded box 35 threadedly attached to the upper pin end 17 of the bit body 18. The upper end of the tubular body may be constituted as a threaded pin 19 threadedly secured to the box portion 20 of a drill pipe section or drill collar thereabove, which forms part of the drilling string B extending to the top of the hole.

The tubular body has a plurality of valve controlled lateral passages or ports 21 therein through which fluid can pass. Such passages or ports will be closed in response to the pressure of the fluid being pumped down through the string of drill pipe B and out through the drill bit A. As illustrated, each passage or port 21 is formed in a separate removable valve body 22 which has an outer end 23 threadedly secured within a companion threaded bore 24 through the body, the inner portion of the valve body having a side seal 25, such as a rubber O ring, disposed in a body groove 26 and sealingly engaging the wall of the bore 24. The body 22 has an intermediate spider portion 27 defined by circumferentially spaced radial arms 28 extending between the central portion 29 and the outer portion of the body. The central or hub portion 29 has a passage therethrough slidably receiving the valve stem 30 of a valve member, the inner portion of which is secured to a valve head 31 adapted to move outwardly into engagement with a companion valve seat 32 surrounding the body passage 21, in order to prevent flow of fluid from the interior of the tubular body 15 to its exterior under certain operating conditions.

60 The valve head 31 is urged in a direction inwardly of the body by a helical compression spring 33 surrounding the valve stem 30 and engaging the valve head 31 at its inner end and the hub 29 at its outer end. The extent of movement of the valve head 31 from its seat is limited by engagement of a suitable stop device 34, such as a nut 65 threaded on the outer end of the stem, with the hub 29. When the valve is in open position, fluid can pass freely through the body passage 21 in both directions between

the interior and exterior of the tubular body member.

It is to be noted that the inner portion of the valve body preferably does not extend inwardly of the inner wall 40 of the body 15. Similarly, the valve head 31, when it engages its companion valve seat 32, need not project inwardly of the inner wall 40 of the body, or the projection is of a relatively minor extent so that there are substantially no obstructions or restrictions to the passage of fluid through the tubular body member 15, or for that matter to the passage of other devices, such as surveying instruments and the like.

The plurality of valve devices is arranged generally radially in the tubular body 15, to provide a total passage area that is quite substantial, and which may be much greater than the total area through the drill bit nozzles 11. During the lowering of the drilling string B through the drilling mud and other fluids in the well bore, the springs 33 will retain the valve heads 31 removed from the valve seats 32. Accordingly, the drilling mud can flow into the drill string B through the drill bit nozzles 11 and also through the body passages 21, which will permit a comparatively ready ingress of the drilling mud into the string of drill pipe to fill the same, and thereby avoiding the building up of high pressures in the drilling mud in the well bore which might be forced into the formation, potentially damaging the latter.

When the drilling operation is to commence, the drill string B is rotated and the drilling mud pumped downwardly through it. The pressure of the fluid will act upon the valve heads 31 and shift them outwardly against the force of the springs 33 into seating engagement with the valve seats 32, closing the by-pass passages or ports 21 against outward flow of fluid from the tubular body 15. Accordingly, all of the drilling mud being pumped through the tubular string will then pass through the drill bit nozzles 11, and if such nozzles have a comparatively small area, the fluid will issue at a high velocity therefrom for direct action upon the bottom of the well bore, upon the cutters 10, or both, to maintain such regions and parts in a clean condition, permitting the cutters to have maximum penetration into the bottom of the hole.

When the drill pipe B is to be removed from the well bore, the pumping action ceases and the relieving of the pressure in the well bore will permit the springs 33 to shift the valve heads 31 inwardly away from their seats 32, thereby opening the by-pass passages 21. As the drill pipe is raised in the well bore, the drilling mud therewithin can drain through the drill bit nozzles 11. It can also drain readily through the open passages 21 in the tubular body 15 to the exterior of the drill string. The ability of the fluid to drain rapidly from the drill pipe B will minimize the swabbing action of the drill string on the drilling mud in the well bore, and will also insure that each stand of drill pipe above the rotary table will be empty and free of drilling mud when such stand of drill pipe is disconnected from the drill pipe therebelow, thereby preventing drilling mud from spilling on the derrick floor and on the rig equipment.

The springs 33 have sufficient compressive force so as to prevent shifting of the valve heads 31 outwardly into engagement with their seats 32 to close the passages 21 during elevation of the drill pipe in the well bore. However, the usual pressures encountered during the drilling operation are more than adequate to overcome the force of the springs 33 and shift the valve heads outwardly of the body into sealing engagement with the valve seats 32 to close the by-pass passages 21.

The inventor claims:

1. In drilling apparatus for a well bore: a tubular drill string including a tubular body; a drill bit secured to the drill string and having a nozzle for discharging fluid from said drill string, said nozzle being normally open to permit fluid to flow upwardly therethrough into the drill string during lowering of the drill string in the well bore and said drill string being open to permit such upward

flow of fluid; said body having a side port for allowing fluid to flow between the interior and exterior of said body, said body having a valve seat surrounding said port; a valve member movable in a laterally outward direction into engagement with said seat to close said port; and spring means engaging said valve member to shift said valve member laterally inwardly away from said seat; said spring means exerting a force sufficient to maintain said valve member away from said seat during elevation of said drill string and drill bit in the well bore to permit simultaneous drainage of drilling fluid from said drill string through said port and bit nozzle.

2. In drilling apparatus for a well bore: a tubular drill string including a tubular body; a drill bit secured to the drill string and having a nozzle for discharging fluid from said drill string, said nozzle being normally open to permit fluid to flow upwardly therethrough into the drill string during lowering of the drill string in the well bore and said drill string being open to permit such upward flow of fluid; said body having a central passage therethrough; said body having a side port for allowing fluid to flow between the interior and exterior of said body, said body having a valve seat surrounding said port; a valve member movable in a laterally outward direction into engagement with said seat to close said port; and spring means engaging said valve member to shift said valve member laterally inwardly away from said seat; said spring means exerting a force sufficient to maintain said valve member away from said seat during elevation of said drill string and drill bit in the well bore to permit simultaneous drainage of drilling fluid from said drill string through said port and bit nozzle; said central passage being substantially free from obstructions when said valve member engages said seat.

3. In drilling apparatus for a well bore: a tubular drill string including a tubular body; a drill bit secured to the drill string and having a nozzle for discharging fluid from said drill string, said nozzle being normally open to permit fluid to flow upwardly therethrough into the drill string during lowering of the drill string in the well bore and said drill string being open to permit such upward flow of fluid; said body having a generally radial bore through its wall; a valve body disposed in said bore and having a port therethrough surrounded by an inner valve seat; a valve member movable in a laterally outward direction into engagement with said seat to close said port; and spring means engaging said valve member to shift said valve member laterally inwardly away from said seat; said spring means exerting a force sufficient to maintain said valve member away from said seat during elevation of said drill string and drill bit in the well bore to permit simultaneous drainage of drilling fluid from said drill string through said port and bit nozzle.

4. In drilling apparatus for a well bore: a tubular drill string including a tubular body; a drill bit secured to the drill string and having a nozzle for discharging fluid from said drill string, said nozzle being normally open to permit fluid to flow upwardly therethrough into the drill string during lowering of the drill string into the well bore and said drill string being open to permit such upward flow of fluid; said body having a generally radial bore through its wall; a valve body disposed in said bore and having a port therethrough surrounded by an inner valve seat; a valve stem slidable in said valve body; a valve head secured to said stem and movable in a laterally outward direction into engagement with said seat to close said port; and a spring engaging said valve body and head to urge said head laterally inwardly away from said seat; said spring exerting a force sufficient to maintain said head away from said seat during elevation of said drill string and drill bit in the well bore to permit simultaneous drainage of drilling fluid from said drill string through said port and bit nozzle.

5. In drilling apparatus for a well bore: a tubular drill string including a tubular body; a drill bit secured to the

drill string and having a nozzle for discharging fluid from said drill string, said nozzle being normally open to permit fluid to flow upwardly therethrough into the drill string during lowering of the drill string in the well bore and said drill string being open to permit such upward flow of fluid; said body having a central passage therethrough; said body having a generally radial bore though its wall; a valve body disposed in said bore and having a port therethrough surrounded by an inner valve seat, said port establishing communication between said central passage and the exterior of said tubular body; a valve stem slideable in said valve body; a valve head secured to said stem and movable in a laterally outward direction into engagement with said seat to close said port; a spring engaging said valve body and head to urge said head

10

15

laterally inwardly away from said seat; said spring exerting a force sufficient to maintain said head away from said seat during elevation of said drill string and drill bit in the well bore to permit simultaneous drainage of drilling fluid from said drill string through said port and bit nozzle; said central passage being substantially free from obstruction when said valve member engages said seat.
